UNITED STATES PATENT OFFICE.

WALTER H. FITZ GERALD, OF BROOKLYN, NEW YORK, ASSIGNOR OF ONE-HALF TO RUBE R. FOGEL, OF NEW YORK, N. Y.

WATCH.

SPECIFICATION forming part of Letters Patent No. 712,185, dated October 28, 1902.

Application filed March 31, 1902. Serial No. 100,686. (No model.)

To all whom it may concern:

Be it known that I, WALTER H. FITZ GERALD, a citizen of the United States, and a resident of New York, Brooklyn borough, in 5 the county of Kings and State of New York, have invented certain new and useful Improvements in Watches, which improvements are fully set forth in the following specification.

10 In a general sense this invention relates to improvements in mechanical structures of that class employed for measuring time and commonly known as "watches," and it relates more particularly to watches in which the 15 movements are reversible and the construction of which is such that each may be readily converted from the so-called "hunting-case" type to the so-called "open-face" type, or vice versa.

20 The object of this invention is to provide a watch which shall be simple, inexpensive, and novel as regards construction, which shall embody features of construction whereby the watch-movement shall be telescopically 25 adjustable with respect to the case-center, thus permitting the employment of a crystal of maximum thickness, at the same time keeping the thickness of the watch as a whole within minimum limits, which shall be positive and reliable in practical service, and 30 which shall possess certain well-defined advantages over prior analogous structures.

The invention consists in the employment of certain parts novel as to form, in the 35 novel disposition and arrangement of the various parts thereof, in certain combinations of the latter, and in certain details of construction, all of which will be specifically referred to hereinafter and set forth in the appended claims.

40 The invention is clearly illustrated in the accompanying drawings, wherein similar reference-numerals denote like parts throughout the several views, and as to said drawings—

45 Figure 1 is a face view of a watch embodying my said improvements, the hinged cover thereof being shown in its open position. Fig. 2 is a sectional view taken along the line 50 *a a* of Fig. 1. Fig. 3 is a view similar to Fig. 2, the movement of the watch being shown

as having been reversed from the position it occupies in Fig. 2. Fig. 4 is a detail perspective view illustrating the movement-ring which I make use of under certain conditions. Fig. 5 is a detail view illustrating the lock-spring which I employ.

55 In a general sense my invention comprises a watch-case, a watch-movement arranged within the said case, and features of construction whereby the said watch-movement is rendered telescopically adjustable with respect to the case proper within prescribed limits.

Having reference to the accompanying 65 drawings, the watch there illustrated comprises primarily a case-center 2, hinged cover 3, pendant 4, bezel 5, and movement-ring 6. The case-center 2 has a continuous or substantially continuous channel at its inner 70 side.

7 represents the watch-movement as a whole. This movement is arranged within the ring 6 in any common and approved manner.

75 The crown 8 fits loosely over the outer end of the pendant 4 and is securely connected with the outer end of the winding-stem 9, the latter being loosely engaged and retained in its place of service within the pendant 4 by 80 a suitable keeper, as 10. The engagement of the keeper 10 with the stem 9 is such that the latter is free to rock somewhat on the former, as from the position indicated in Fig. 3 to the position indicated in Fig. 2 of the 85 drawings, or vice versa, and in this operation of the stem 9 the crown 8 moves therewith accordingly, sufficient play between said crown and the adjacent end of the pendant 4 being provided for this purpose.

90 11 is an intermediate ring let into the channel of the case-center 2, and 12 denotes the lock-spring which I employ, the said lock-spring being of ordinary construction, save that it is provided with an elongated transverse opening 13. The ring 11 is provided with an opening 14, and in this instance the case-center 2 is also provided with an opening 15.

95 The movement-ring 6 has two elongated 100 transverse openings 16 and 17, formed in diametrically opposite segments of said move-

ment-ring. The opening 17, by preference, is just sufficient in width to permit a free turning of the many-sided or inner end portion of the winding-stem 9, as for winding or 5 adjusting purposes, and the opening 16, which received the pivot 18, here shown as rigidly connected with the intermediate ring 11 and projecting inwardly therefrom, conforms in width to the diameter of said pivot. Thus 10 the pivot 18 and winding-stem 9 serve as trunnions on which the watch-movement turns when undergoing its reversing action. The openings 14, 13, and 15, by preference, accord in width each with the opening 17, though 15 they may be somewhat larger or of different form so long as they permit the winding-stem 9 to undergo the rocking movement herein-before referred to, as on the keeper 10.

19 denotes the crystal of the watch, and 20 when the parts occupy the positions indicated in Fig. 2 of the drawings this crystal projects somewhat beyond the bezel 5, and when the parts occupy the positions shown in Fig. 3 of the drawings the cap 20 fits snugly into the 25 bezel 5, thus completely closing that side of the case of the watch.

It will be observed that the distance from the outermost point of the crystal-surface to the center of the watch-movement is greater 30 than the distance from the center of the watch-movement to the outermost point of the cap 20. Therefore if the reversing action of the 35 watch-movement were controlled by a fixed axis for such movement it would be impractical to close the hinged cover 3 without crushing the crystal 19, particularly if the latter should be of substantial thickness and assuming that the parts occupy the positions indicated in Fig. 3 of the drawings. The 40 usual method of overcoming this objectionable feature is to increase the dish of the cover 3, and accordingly increase the thickness of the watch as a whole, with the further objectionable result of giving to the watch a lop-sided appearance. I overcome the foregoing 45 objections by providing parts and features of construction substantially as herein described and whereby the watch-movement is rendered telescopically adjustable with respect to the 50 case proper.

In practice where the movement-ring 6 is employed this accompanies the watch-movement 7 in the latter's shifting or telescopic action with respect to the watch-case proper, 55 and this action on the part of the watch-movement is permitted by reason of the openings 16 and 17 being suitably shaped to this end.

In operation, assuming that the parts occupy the positions indicated in Fig. 2 of the 60 drawings, where they are positioned to form a so-called "open-face" watch, and the user desires to convert such watch into a so-called "hunting-case" watch, it is only necessary to open the cover 3, turn the dial or crystal side 65 of the watch uppermost, thus allowing the movement 7, with the ring 6, where the latter is used, to descend somewhat as by gravity,

whereupon the movement 7 and ring 6, if the latter be employed, may be reversed, so as to present the cap 20 to the bezel 5. Then if 70 the watch is properly positioned the watch-movement and the ring containing it will fall as by gravity to the positions shown in Fig. 3 of the drawings, under which conditions the cap 20 enters the bezel 5 and serves as a 75 closure member for that side of the watch-case, while the dial or crystal side of the movement 7 is in its usual position in the so-called "hunting-case" type of watches.

Any suitable and approved fastening device or devices may be employed for locking the watch-movement against its reversing action, as when brought to the position shown in Fig. 2 of the drawings or to the position shown in Fig. 3 of the drawings. 80 85

The engagement of the inner end of the winding-stem 9 with the arbor 21 is such that while ample play is left to permit the telescopic action of the movement 7, herein referred to, the joint action of said stem with 90 said arbor, as for winding purposes, is not objectionably affected.

It will be seen that my improvements are particularly well adapted for the purposes for which they are intended, and, further, that 95 the construction herein shown and described may be modified to some extent without materially departing from the spirit and principle of my invention.

Having fully described my invention, what 100 I claim, and desire to secure by Letters Patent, is—

1. A watch comprising a case and a watch-movement, the latter being pivoted within the case for reversing action, thus converting an 105 open-face into a hunting-case watch, or vice versa, said movement being adjustable with respect to the case in a direction at right angles to the planes of the faces by direct longitudinal movement, within prescribed limits. 110

2. A watch comprising a case, a movement-ring, and a watch-movement, the said movement-ring being pivoted within the case, the 115 said watch-movement being arranged within the said ring, and said ring and watch-movement being jointly adjustable in a direction at right angles to the planes of the faces of the case by direct longitudinal movement.

3. A watch comprising a case, a watch-movement embodying a winding-arbor and being 120 arranged within the case; and a winding-stem, the latter movable in radial planes and engaging at its inner end said winding-arbor, the said watch-movement being adjustable in a direction at right angles to the planes of the 125 faces of said case by direct longitudinal movement.

4. A watch comprising a case, a movement-ring, a watch-movement embodying a winding-arbor, the said movement-ring being arranged within the case, the said watch-movement being arranged within said ring, and said ring and watch-movement being jointly 130 adjustable in a direction at right angles to the

planes of the faces of the case by direct longitudinal movement; and a winding-stem movable in radial planes, extending through said movement-ring, and engaging at its inner end the winding-arbor aforesigned.

5. A watch comprising a case and a watch-movement, the latter being pivoted for reversing action within the case-center and for limited adjustment in a direction at right angles to the planes of the faces of said case by direct longitudinal movement.

6. A watch comprising a case, a movement-ring, and a watch-movement, the said ring being pivoted for reversing action within the case-center and for a limited adjustment in a direction at right angles to the planes of the faces of the case by direct longitudinal movement, and said watch-movement being arranged within said ring.

15 7. A watch comprising a case, a watch-movement pivoted for reversing action within the case-center, and parts intermediate of said

case and movement whereby the latter may undergo both a reversing action within the case-center and a limited adjustment in a direction at right angles to the planes of the faces of said case by direct longitudinal movement.

25 8. In combination, in a watch, a watch-case having a hinged cover at one side and a bezel at the opposite side, a movement-ring within said case, a capped watch-movement arranged within and accompanying said ring in the latter's movements, and pivots intermediate of said movement-ring and said case whereby 30 said ring may undergo both a reversing action within the case-center and a limited adjustment in a direction at right angles to the planes of the faces of said case by direct longitudinal movement.
